Inventor:

Henry Birsh.

UNITED STATES PATENT OFFICE

141,235

DESIGN FOR A PROPELLER FOR DIAMETER CONTROL

Henry Birsh, New York, N. Y.

Application July 18, 1942, Serial No. 107,591

Term of patent 14 years

(Cl. D71—1)

To all whom it may concern:

Be it known that I, Henry Birsh, a citizen of the United States and a resident of the city, county, and State of New York, have invented a new, original, and ornamental Design for a Propeller for Diameter Control, of which the following is a specification, reference being had to the accompanying drawing forming part thereof.

Figure 1 is a front perspective view of a propeller for diameter control showing my new design; and

Figure 2 is a side elevational view thereof.

The characterizing features of my new design reside in the partly straight blade and continuation of the rounded and arcuated elbow which inserts into the hub as shown.

I claim:

The ornamental design for a propeller for diameter control, as shown and described.

HENRY BIRSH.
